UNITED STATES PATENT OFFICE

ALBERT KLEIN, OF NEW YORK, N. Y.

DESIGN FOR AN ASH TRAY OR THE LIKE

Application filed December 26, 1929. Serial No. 33,917. Term of patent 3½ years.

To all whom it may concern:

Be it known that I, ALBERT KLEIN, a citizen of the United States, residing in Bronx, county of New York, and State of New York, have invented a new, original, and ornamental Design for Ash Trays or the like, of which the following is a specification, reference being had to the accompanying drawing, forming part thereof.

I claim as my invention:

The ornamental design for an ash tray or the like substantially as shown.

ALBERT KLEIN.
